United States Patent Office

Des. 191,783
Patented Nov. 21, 1961

191,783

MOP FRAME

Max Spotniz, Hartford, Conn.
(% La Pointe Industries, Inc., Rockville, Conn.)

Filed May 15, 1961, Ser. No. 65,179

Term of patent 14 years

(Cl. D9—2)

FIG. 1

FIG. 2

FIG. 3

FIG. 4

FIG. 1 is a perspective view of a mop frame with the handle socket in raised position, embodying my new design;

FIG. 2 is a bottom plan view with the handle socket in lowered position;

FIG. 3 is an end elevational view taken from the right of FIG. 2; and

FIG. 4 is a cross-sectional view taken through line 4—4 of FIG. 2.

I claim:

The ornamental design for a mop frame, substantially as shown.
